CLUTCHING AND DRIVING MECHANISM

Emil Ericksson, Chicago, Ill., assignor to Standard Process Corporation, Chicago, Ill., a corporation of Delaware

Original application September 22, 1932, Serial No. 634,406. Divided and this application September 5, 1936, Serial No. 99,670

24 Claims. (Cl. 101—171)

The present invention relates to novel clutching and driving mechanism and more specifically to such mechanism as employed in the starting and driving of printing presses.

- 5 While the clutching and driving mechanisms disclosed in the present application are of particular advantage when used with a printing press it is to be understood that they are capable of wider application as for treating strip or web material as by coating and the like. For the purposes of illustration, the present invention will be described in connection with a multiple impression printing press of the type shown and described in my co-pending application Serial No. 15 634,406, filed September 22, 1932, which has since matured into United States Patent No. 2,103,812 issued December 28, 1937, wherein the present invention is described, the instant application being a division of said co-pending application.
- 10 20 A primary object of the present invention resides in the provision of novel clutching and driving mechanisms designed to advance a web or strip of material around an idling cylinder and between a plurality of positively driven cylinders.
- 25 A further object of the present invention is to provide novel web or strip advancing means having a normally idling cylinder and at least one positively driven cylinder between which the web or strip is drawn with a variable speed friction
- 30 clutch arranged to initiate drive of the normally idling cylinder and bring it and the web or strip up to operating speed independently of the positively driven cylinder.

Another object of the present invention resides 35 in the provision of novel web or strip advancing means having a centrally disposed freely rotatable cylinder and a plurality of driven cylinders spaced about the central cylinder to advance a web or strip under proper tension with means for initially starting the advancing means without 40 imposing injurious strains on the web or strip.

A further object of the present invention resides 45 in providing a multi-color printing press having a normally idling impression cylinder and a plurality of positively driven printing cylinders positioned thereabout with a main driving gear designed to rotate the impression cylinder under certain phases of operation and to mesh with secondary driving gears designed to drive the printing cylinders.

Another object of the present invention is to 50 provide a novel printing press having a normally idling impression cylinder with a planetary gear system designed to provide a variable speed drive

connection for said impression cylinder to initially start the press.

A further object of my invention is to provide a novel driving mechanism for use on a printing press having an impression cylinder normally free 5 to rotate, and a plurality of driven printing surfaces circular in cross section spaced about the impression cylinder to advance and print upon a web maintained under proper tension.

A still further object of my invention is to provide a printing press having a freely rotatable impression cylinder and positively driven printing cylinders from which rotation is imparted to said impression cylinder to propel a web therebetween with means to initially start and accelerate said 15 impression cylinder to prevent tearing or distortion of the web.

Other objects of the invention will appear from the following description taken in connection with the attached drawings wherein:

20

Figure 1 is a side elevation of a printing press embodying a preferred form of the novel driving mechanism of the present invention.

Figure 2 is a fragmentary section in side elevation of the mechanism for initially starting the 25 impression cylinder and accelerating it to the desired operating speeds.

Figure 3 is a fragmentary section of the main driving means.

Figure 4 is a fragmentary section showing the 30 mechanism for driving and obtaining registry of the printing cylinders.

Figure 4a is a fragmentary view partly in section illustrating the mechanism for selectively driving one of the printing cylinders.

35

Figures 5 and 6 are top plan elevational views of the sliding key used in the mechanism of Figure 4.

Figures 7 and 8 are side and end elevational views of the helically slotted sleeve provided for 40 cooperation with the key of Figures 5 and 6.

With continued reference to the drawings wherein like reference numerals are used to designate the same parts throughout the several figures, a multiple impression printing press 11, 45 including a pair of spaced supporting frames 12 and an outside auxiliary frame 13 positioned on a base or sole plate 14, is provided with a preferred embodiment of the novel clutching and driving mechanism of the present invention. 50 Frames 12 are preferably provided with four apertures 15 positioned so that when frames 12 are mounted on sole plate 14, the apertures are opposite one another. The upper right quadrant of each frame 12 (referring to Figure 1) is pref- 55

erably formed separately from the remainder of the frame and pivoted at 16 to permit of raising of the frame section to secure access to the impression roller within.

5 A normally idling impression cylinder 17 having a suitable impression surface 18 is rotatably supported on supporting frames 12 in the following manner: Impression cylinder 17 is preferably secured to hub 21 (Figure 2) which rotates on shaft 22, by spokes 23, thus providing a light, but rigid and strong structure. Shaft 22 is provided with enlarged sections 24 over which hub 21 is forced into position against a shoulder 25 formed on one of sections 24. Shaft 22 is journaled in combined radial and thrust bearings 26 supported in frame members 12. Thrust bearings 26 may, if desired, be of the type comprising cup rings 27 and cones 28 although it is to be understood that any suitable form of anti-friction bearing may be employed.

Bearing housing 29 is retained between the left hand frame member 12 (Figure 2) and cap or cover member 31, secured to frame member 12 by suitable connection means, for example, 25 bolts 32 (Figure 1). Bearing 26 is held in proper relation to the end of shaft 22 by cap 33 secured to shaft 22 by bolts 34. A ring member 35 is spaced from cap 33 and secured by bolts 35' to bearing housing 29 to hold the bearing assembly together. This arrangement permits the withdrawal of shaft 22 by removing cap 33, there being no necessity for disturbing the bearing assembly.

Packing 36 is provided to prevent the escape 35 or leakage of the lubricant supplied to bearing 26. A cover 37 retained in position by suitable means, as for example, bolts 38 engaging frame member 12 and cap 31 provides a lubricant chamber 39 and maintains the entire bearing assembly in position in the frame 12.

Right hand frame member 12 is provided with a combined radial and thrust anti-friction bearing 40 to receive the opposite end of shaft 22. Bearing 40 is mounted on frame member 12 45 under cover or cap member 41 which is secured to frame 12 by suitable means. A ring 42 secured to bearing housing 40 by suitable bolts 43, holds a packing 44 against shaft 22 to prevent leakage and escape of lubricant from bearing 40. A ring 45 surrounds bearing housing 40 and ring 42 and is secured to frame member 12 and cap member 41 by suitable bolts 46.

Caps 31 and 41 are secured to frames 12 at an angle, preferably 45°, as seen in Figure 1, so that cylinder 17 may be removed or reground through the opening provided by the hinged quadrants of frames 12.

Frames 13 supports the ends of stub-shafts 47 journalled in webs 48 of frames 12 (Figures 1 60 and 4). Shafts 47 carry frames 49 and swinging brackets 50 which in turn support printing cylinders 51, 52, 53 and 54 and their drive mechanisms spaced about the periphery of cylinder 17. Stub-shafts 47 are journalled in webs or projections 55 of auxiliary frame 13, the projection 55 opposite printing cylinder 54 being preferably formed on a detachable portion of auxiliary frame 13 in order that cylinder 51 and its associated mechanism may be swung bodily around 70 hinge 16.

The press thus far briefly described is shown and described in copending application Serial No. 634,406. Since the general press construction does not form any part of the present invention, a more detailed description thereof will

not be given in this application. A novel friction clutch of the present invention as applied to the press of Serial No. 634,406 briefly described above will now be described.

Printing or treating cylinders 51, 52, 53 and 54 in combination with impression surface 18 advance the material, preferably in the form of a web, which is to receive an impression or impressions therefrom or to be otherwise treated, and are driven by novel means to be hereinafter described in detail. For the sake of simplicity, cylinders 51, 52, 53 and 54 will be hereinafter called printing cylinders although it will be obvious from the foregoing that the invention embraces other treating operations than printing. 15

A gear 56 is keyed by suitable means, as key 57 or otherwise associated in driving relationship with a hollow shaft 58 (Figure 2) which is aligned with shaft 22 and supported at its end adjacent shaft 22 in a bearing 59 in main frame 20 member 12, and at the other end by a supporting mechanism generally indicated at 61 including brake drum 62 for a purpose to be described.

Gear 56 is driven from a pinion 63 which is keyed or otherwise secured on a main drive shaft 25 64 which is in turn driven by a pulley wheel 65. A hand wheel 66 is keyed or otherwise secured to main drive shaft 64 so that the mechanism of press 11 may be manually moved for the purpose of threading the material to be printed or to 30 move the printing cylinders or material for any purpose for example when making any of the necessary adjustments, described in detail in co-pending application Serial No. 634,406.

Shaft 22 is driven in the following manner 35 from gear 56. A constantly engaged dog clutch member or ring 67 is secured to the end of shaft 22, between the end of shaft 22 and bearing member 59 by suitable means 68. A cover member 69 secured to frame member 12 and cap 41 by 40 suitable means 71 is provided for protecting bearing 59 and clutch 67. Cover member 69 contains suitable packing as at 72 to prevent the escape of lubricant.

Hollow shaft 58 at its end opposite bearing 59 is provided with a bearing ring member 73 secured for rotation with shaft 58 by a key 74. Hollow shaft 58 is rotatably supported through bearing ring 73 and an anti-friction bearing 75 carried by a member 76. Member 76 is rotatably supported by an anti-friction bearing 77 mounted in frame member 13 and held therein by a bearing cap 78 secured to frame member 13 by suitable means 79 (Figure 1). Impression cylinder drive shaft 81 is received within shaft 58 50 one end thereof extending within member 76. Suitable means, for example, keys 82, in keyways 83 of member 76 and shaft 81 connect shaft 81 to rotatable member 76. 55

Shaft 81 is provided at its ends with spines 84 60 in engagement with splines 85 in clutch ring 67 for the purpose of driving impression cylinder 17 when desired through mechanism 61. The connection afforded by splines 84 and 85 provides a flexible driving connection which permits cylinder shaft 22 to be free of distorting stresses which might otherwise occur when power is transmitted from main driving gear 56, and eliminates a possible source of inaccuracy in the location of impressions received from the printing cylinders. Shafts 22 and 81, so connected, comprise a sectional shaft through which impression cylinder 17 may be driven but which is a normally idling shaft. 65

Hub 86 of bevel gear 87 is secured to member 75

76 for rotation therewith by suitable means, for example set screw 88. A shoulder 89 on member 76 insures the proper positioning of gear 87 with respect to member 76. A second bevel gear 91 is mounted to rotate on shaft 58 and is secured to the hub of gear 56 for rotation therewith by means of set screw 92. Bevel pinion 93 is in mesh with bevel gears 87 and 91 and is mounted on bevel pinion shaft 94 carried in hub 95 and an aperture in rim 96 of brake drum 62. Pinion shaft 94 is retained in position by suitable means, for example, set screw 97. Brake drum 62 is rotatably journaled on hollow shaft 58 by means of bearing bushings 98. A suitable fitting 99 provides for a supply of lubricant to bearing bushings 98.

When desired brake drum 62 is restrained from rotation by brake band 101. Brake band 101 is adjusted by means of bolts 102 (Figure 1) and nuts 103 cooperating with ears 104. The ends of brake band 101 are connected to pins 105 (Figure 1) in levers 106. Levers 106 are carried on frame member 13 by bolts 107. Arms 108 of levers 106 are connected by toggle links 109 so that they may be spread apart to tighten brake band 101 on brake drum 62.

Arm 111 of toggle lever 109 may be connected to any suitable operating device or may be provided with a handle for manual operation. I have disclosed by way of example a solenoid magnet 112, core 113 of which is operatively connected by link 114 to arm 111. Pins 115 in frame member 13 serve as stops for levers 106. Impression cylinder 17 may be caused to rotate by drawing plunger 113 of solenoid 112 upwardly. Toggle ears 109 spread levers 108 which contract brake band 101 by movement of arms 106 toward each other.

Rotation of brake drum 62 is thus prevented and bevel pinion shaft 94 remains stationary. Rotation is then imparted to impression cylinder 17 from gear 56 through bevel gear 91, bevel pinion 93, bevel gear 87 and shaft 81.

With brake drum 62 free to rotate, differences in rotational speed between gear 56 and impression cylinder 17 are permitted by rotation of brake drum 62 at some intermediate speed. If, for example, impression cylinder 17 is stationary, brake drum 62 will rotate at about one-half the speed of main drive gear 56 due to planetary action of pinion 93.

Main drive shaft 64 carrying pulley 65 and drive pinion 63 is journaled in frame members 12 and 13 on anti-friction bearings 116. Bearing 116 in frame member 12 is supported in a cup 117 and sealed with a lubricant seal 118. A divided collar 119 which is secured together by suitable means 121 retains cup 117 in position in frame 12. A seal 122 is provided for divided collar 119. Divided collar 119 is retained in position on frame member 12 by suitable fastening means, for example, bolts 123. Bearing 116 in frame member 13 is mounted in a cup 124. A cover plate 125 retains cup member 124 in position on frame member 13. Suitable means 126 connect cover plate 125 to frame member 13, lubricant seals 127 being provided as shown.

Gear 56 also meshes with gears 128 which are adapted to drive the printing cylinders 51, 52, 53 and 54. Since the printing cylinder driving mechanisms are identical, only one of the mechanisms will be described. In this connection, the drive for printing cylinder 54 has been chosen for illustration.

Gear 128 is keyed or otherwise secured to sleeve

129 which rotates on bearing bushings or sleeves 130 on shafts 47 between frames 49 and swinging brackets 50. Suitable lubricant fittings 130' provide for a supply of lubricant to the bearing surfaces on shaft 47.

Printing cylinder 54 is mounted upon a shaft 131 which is supported in bearings 132 and 133 carried by swingable frames 49, which are pivotally mounted on webs 48 by means of stub-shafts 47. Bearing carrying frame 49 on left-hand frame member 12 (Figure 4) is made up of two parts 135 and 136 placed back to back and held together by suitable fastening or clamping means. Frame 49 on right-hand frame member 12 is made up in a like manner of parts 137 and 138 held back to back by suitable clamping means.

Parts 135 and 136 and parts 137 and 138 of swingable frames 49 form bifurcated portions which fit over and contact with webs 48, which together with shafts 47 form a pivot joint permitting frames 49 to swing freely but without twisting or lateral movement thereof. Inaccuracies in the register of printing cylinders 51, 52, 53 and 54 are prevented due to the above described pivot point.

Left hand frame 49 is provided at its end opposite pivot points 47 with projections 139 and 140 provided with apertures 141 for connection with means, described in co-pending application Serial No. 634,406, for moving printing cylinders 51, 52, 53 and 54 selectively or collectively into and out of contact with impression surface 18 of impression cylinder 17. Right hand frame 49 is provided with projections 142 and 143, apertured at 144 for a like purpose. Since such means form no part of the present invention, a detailed description thereof in the present case is believed unnecessary.

A gear 145 is keyed by means of a key 146 or other suitable means to a sleeve 147 which is provided with an aperture 148 for driving engagement with a clutch pin 149. Pin 149 is seated in an aperture 151 in a hub member 152 of a hand wheel 153, which is secured to hub 152 by suitable means as for example bolts 154. Clutch pin 149 extends further into a radial aperture 155 in a sleeve 156 which is connected for rotation with hub 152 by means of a suitable key (not shown) fitting in keyway 157 in sleeve 156 and a suitable keyway (not shown) provided in hub 152. Shaft 131 is provided with a recess 158 and a slot 159. An elongated centrally located bore 160 is also provided in shaft 131.

A key 161 (Figures 5 and 6) is seated within recess 158 of shaft 131 for longitudinal reciprocation therein. A projection 162 of key 161 projects through slot or aperture 159, and is received within a transverse notch or aperture 163 formed in end 164 of a reciprocable rod or shaft 165. Key 161 is provided with a spline 166 of relatively long pitch received in a helical slot 167 (Figures 7 and 8) of like pitch in the circumferential wall of sleeve 156.

A novel adjusting means including key 161 and rod 165 accurately positions the printed impression axially of the web while the press is operating at full speed. To this end bore 171 of swingable bracket member 50 is provided with threads 172 which engage threaded portion 173 of barrel or sleeve 174. Barrel 174 may be manually rotated by a hand wheel 175 for axial movement in bore 171 by engagement of threads 172 and 173. Periphery 176 of hand wheel 175 is provided with graduations, the interval between

the graduation corresponding to definite distances measured axially of impression surface 18 and hence transversely of the web of material. The graduations may, if desired, correspond to 5 thousandths of an inch as measured on the web.

Shaft 131 is associated with printing cylinder 54 and is caused to move axially with threaded barrel 174 by anti-friction bearing ring 177 held against axial movement on reduced portion 178 of shaft 131 between collars 179 and 181, mounted 10 on reduced portions 182 and 178 respectively of shaft 131. Collar 179 is in abutting engagement with the edge of hand wheel hub body 172 and clutch sleeve 156. Collar 181 engages sleeve 184 15 which is secured to the end of the shaft 131 by suitable means, for example, set screws 185 which permit collar 184 to be axially adjusted prior to the insertion of set screws 185. Stationary thrust bearing ring 186 engages an annular projection 187 of threaded barrel 174. Corresponding stationary thrust bearing ring 188 engages a threaded cover or cap 189 the threads of which are in engagement with threads on the interior 20 of barrel 174.

25 Suitable anti-friction bearings, for example, balls 191 transmit end thrust of thrust bearing ring 177 to stationary thrust bearing rings 186 and 188. Undesired end play of thrust bearing rings 177, 186 and 188 may be prevented by adjustment of threaded cover 189 which may be secured after adjustment by set screws 192.

From the mechanism thus far described it will be seen that as hand wheel 175 is manipulated to move threaded barrel 174 in the desired direction, shaft 131 will be moved axially by means of thrust bearing ring 177 and stationary thrust bearing ring 186 or 188 depending upon the direction of movement for the adjustment desired. Any observed transverse variations of the printed impressions on the web may be corrected by manipulation of hand wheel 175 associated with the printing cylinder to be adjusted. This may be done at any operating speed or before initial starting of the press. The graduations on hand 40 wheel 175 facilitate the setting of the printing cylinder to the desired point when out of register. The printed web is measured to determine how much each cylinder is out of register and the hand wheel for that printing cylinder is turned through 45 the number of graduations corresponding to the distance measured on the web.

Key 161 may be adjusted longitudinally in recess 158 on shaft 131 for the purpose of changing the angular position of gear 145 with respect to shaft 131 so that inaccuracies in the longitudinal location of the printed impression from the printing cylinder may be corrected and perfect register restored at any speed of the press or with the press at rest. To this end a hand wheel 193 having a barrel 194 formed thereon is secured in barrel 174.

Periphery 195 of hand wheel 193 is also provided with graduations, the interval between the graduations corresponding to definite distances 55 measured longitudinally of the web. The graduations may, if desired, correspond to thousandths of an inch as measured on the web. Barrel 174, in order to receive barrel 194, is provided with an interiorly threaded portion 196 which receives threads 196' provided on barrel 194. Barrel 194 is rotated by hand wheel 193 to effect longitudinal movement thereof with respect to barrel 174. Key 161 and shaft 165 are moved longitudinally in bore 160 by means of thrust bearing assembly 197 (similar in construction to the bearing assem-

bly described in connection with hand wheel 175) positioned in barrel 194.

As hand wheel 193 is rotated in either direction barrel 194 will be moved longitudinally with respect to the barrel 174 on threaded connection 196. Thrust bearing assembly 197 will impart the longitudinal movements of barrel 194 to shaft 165 in a manner that will be readily apparent from the drawings.

Thrust bearing assembly 197 includes bearing 10 ring 198 and bearing members 199 and 201 between which are interposed suitable anti-friction bearings, for example, balls 203. Bearing members 199 and 201 are retained on rod 165 by suitable means, for example, cap screws 204 and annular member 205.

Thrust bearing assembly 197 is positioned between shoulder 206 and cover plate 207. Cover plate 207 is retained in position by suitable fastening means, for example, cap screws 208. To prevent undesired twisting or rotation of shaft 165, key 209 may be employed to connect the end of shaft 131 to shaft 165.

Suitable means 211 provides for a supply of lubricant to the parts. Lever 212 and clamping 25 bolt 213 are employed to clamp barrels 174 and 194 in fixed relationship. Links 214 and 215 provide for differences in position of hand wheel 193 and barrel 174.

From the description just given, it will be seen 30 that key 161 is reciprocated in recess 158 by hand wheel 193 and shaft 165. Reciprocation of these members varies the angular relationship of gear 145 and shaft 131 thereby affecting the longitudinal registering of the impressions on the web of 35 material. Undesired movements of sleeve 156 on shaft 131 are prevented by a collar 217 secured to shaft 131 by suitable means, for example, key 218, beyond the point 219 of slight reduction in the diameter of shaft 131. Collar 217 may, if desired, abut inner bearing sleeve 221 which in turn 40 abuts shoulder 222 at the point of reduction in diameter of the shaft 131 thus aiding in preventing longitudinal movement of sleeves 147 and 156 on shaft 131.

Inner bearing sleeve 221 located on the portions 45 of the shaft 131 within frame members 49 is of a length greater than that of bearings 132 and 133 and thus permits longitudinal movement of shaft 131 for the purpose of obtaining accurate positioning of impressions from printing cylinders 50 51, 52, 53 and 54 laterally of the web of material under control of the adjusting means previously described. Bearing 133 and outer bearing sleeve 224 are retained by cover members 225 secured to frame members 137 and 138 by suitable fastening 55 means as for example screws 226. Hand wheel hub body 152, connected for rotation with sleeve 156 by means of pins 227 fitting within apertures 228 in sleeve 156, prevents axial movements of 60 hand wheel hub 152 along shaft 131.

A set screw 229 in hand wheel hub 152 frictionally engages groove 231 of clutch pin 149 to hold clutch pin 149 in position with its shank engaged in arcuate notch 148 of sleeve 156 whereby gear 65 145 may drive shaft 131, or with notch 232 positioned to the left whereby sleeve 147 is free to rotate without imparting rotational movement to sleeve 156.

Operation

70 Power is applied to main drive shaft 64 (Figure 3) and is transmitted by means of pinion 63 and gear 56 to the several intermediate printing cylinder drive gears 128. It will be seen that as 75

gears 128 and bearing frames 49 and brackets 50 have a common center, driving force will be applied from intermediate printing cylinder drive gears 128 to printing cylinder drive gears 145 5 regardless of the angular position of swinging frames 49 and brackets 50 within the limits of their movement. Rotation is thus imparted to printing cylinder shafts 131 with printing cylinders 51, 52, 53 and 54 either in or out of printing 10 contact with the web material.

If it is desired at any time to stop rotation of any one of printing cylinders 51, 52, 53 and 54 this may be done by loosening set screw 229 and rotating clutch pin 149 until notch 232 permits free movement of sleeve 147. Sleeve 147 will then rotate idly on sleeve 156 without imparting movement to its corresponding printing cylinder shaft. It is thus possible to print at will from any one of the several printing cylinders 20 or any group thereof. The printing cylinders not in use may remain idle.

As hereinbefore described, impression cylinder 17 rotates freely during normal printing operation, being driven by the web material which in 25 turn is advanced by the positively driven printing cylinders 51, 52, 53 and 54. It is, however, desirable that impression cylinder 17 be initially started and accelerated to normal operating speed by the power driven means and friction clutch previously described in order to avoid distortion or 30 possible rupture or breakage of the web material and possible injuries to the etched surface of the printing shells which may result from frictional contact during acceleration of printing cylinder 35 17.

In order to effect the positive acceleration of cylinder 17 the press 11, with printing cylinders 51, 52, 53 and 54 out of contact with impression cylinder 17, has the web of material threaded therethrough after insertion of the web between the guide rolls and tensioning means described in co-pending application Serial No. 634,406. The web material is then passed between each of the printing cylinders and impression surface 18, by rotating the press slowly either by the main power drive or hand wheel 66.

Brake band 101 during this time is preferably engaged so that the web is drawn around cylinder 17, due to the positive drive imparted thereto. After the material has been passed between the several printing cylinders and cylinder 17, it is taken over guide rolls and passed under a drier or led directly to a reeling stand or disposed of in the desired manner. With the press in this 55 condition, it is ready for printing.

To initiate printing on the web material, impression cylinder 17 is started and accelerated to normal running speed by tightening band 101 of starting mechanism 61 which will smoothly and 60 rapidly accelerate the impression cylinder to normal operating speeds, at which speed the printing cylinders may be collectively placed in operative contact with the paper by operation of the mechanism described in co-pending application 65 Serial No. 634,406. The brake band of starting mechanism 61 after the operating speed is reached may be released as impression drum 17 is now being driven by the several printing cylinders 51, 52, 53 and 54 overlying the impression surface 18. The press, due to the use of the 70 variable friction clutch 61, is accordingly brought up to operating speed without any strain on the web of material.

The invention may be embodied in other specific forms without departing from the spirit or

essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by 10 United States Letters Patent is:

1. A printing press comprising an impression cylinder, a printing cylinder, means to drive said printing cylinder, said driven printing cylinder normally driving said impression cylinder; and means to accelerate and initially drive said impression cylinder from said printing cylinder drive means.

2. A printing press comprising an impression cylinder; a printing cylinder, said impression cylinder and said printing cylinder being adapted to receive and propel a strip therebetween, means to drive said printing cylinder positively, said impression cylinder normally rotating idly in contact with the strip between said cylinders; and means to drive said impression cylinder positively, said last mentioned means comprising a variable speed clutch means.

3. A printing press comprising a normally idle impression cylinder; a plurality of positively driven printing cylinders, said impression cylinder and said printing cylinders being adapted to receive and propel a strip therebetween; and means to drive said impression cylinder positively, said last mentioned means comprising variable speed clutch means.

4. In a printing press comprising in combination an idle impression cylinder and a plurality of driven printing cylinders, the contact or pressure between the impression cylinder and the printing cylinders propelling a web to be printed between them; means to initially start and accelerate said impression cylinder so that the impression can be thrown in while the printing cylinders are running without danger of tearing or distortion of the web, said means comprising a friction clutch and a solenoid.

5. In a printing press having an impression cylinder and a plurality of printing cylinders adapted to engage and propel a strip of material to be printed, the combination of a main drive shaft, a driving pinion secured to said shaft, a hollow driven shaft, a driven gear secured to said hollow shaft adapted to mesh with said driving pinion, a shaft adapted to support and drive said impression cylinder, an extension on said impression cylinder supporting shaft, said extension extending through said hollow shaft and connected in driving relation thereto by means of a variable speed clutch, a driven shaft for each of said printing cylinders, a gear on each of said driven shafts meshing with said hollow shaft driven gear, and means to disengage said variable speed clutch and permit said impression cylinder to idle during normal operation of said press.

6. In a printing press having a normally idling impression cylinder, means for initiating operation of said cylinder comprising a driven shaft, a bevel gear secured to said driven shaft, a shaft supporting said impression cylinder, a second bevel gear secured to said supporting shaft, a housing surrounding said bevel gears, a bevel pinion mounted in said housing and designed for constant engagement with said bevel gears, and a friction band encircling said housing adapted

- to lock said housing against rotation and to transmit torque through said second bevel gear to said supporting shaft.
7. A clutch for use in initiating operation of a printing press having a normally idling impression cylinder comprising driving and driven shafts, a gear secured to said driving shaft, a second gear secured to said driven shaft, a housing surrounding said gears and rotatably supported by one of said shafts, a planetary pinion rotatably supported by said housing and in constant engagement with said gears, and means for locking said housing against rotation to establish a driving connection between said gears and their associated shafts.
8. The combination defined in claim 7 wherein said last-mentioned means comprises a friction band encircling said housing, a pair of crank arms, the adjacent ends of which are connected to the ends of said friction band, a toggle connection connecting the opposite adjacent ends of said crank arms and means for operating said toggle connection to engage said friction band and said housing.
9. A driving mechanism for advancing a strip or web of material through a treating machine comprising a normally idling cylinder for supporting said web, a plurality of positively driven treating cylinders operable to grip said web between them and said first mentioned cylinder and advance said web through said machine, means for driving said plurality of cylinders and manually operable clutching elements for selectively connecting one or more of said plurality of cylinders to said driving means.
10. The combination defined in claim 9 wherein driving means is provided for said normally idling cylinder, said means including a variable speed clutch for positively driving said normally idling cylinder to initially accelerate said web to operating speed whereby injury of said web and said treating cylinders is obviated.
11. A driving mechanism for a web treating machine having a normally idling web supporting cylinder and a plurality of positively driven treating cylinders carried in pivoted swingable frames and operable to advance said web over said idling cylinder comprising a main drive shaft, a driving pinion on said drive shaft, an intermediate drive shaft, a driven gear mounted on said intermediate drive shaft for engagement with said pinion, a drive gear for each of said driven treating cylinders rotatably mounted on the pivot of each of said swingable frames and operatively engaging said driven gear, and a driven gear mounted in each of said swingable frames operable to engage said treating cylinder drive gear and transmit the driving force to said driven treating cylinders.
12. In a web printing press having a normally idling impression cylinder and a plurality of positively driven printing cylinders for normally driving said web, the combination of a main drive shaft, an intermediate drive shaft, a normally idling shaft carrying said impression cylinder, a driven shaft for each of said printing cylinders operable to drive said cylinders, means interconnecting said main drive shaft and said intermediate drive shaft and operable to establish a driving connection therebetween, means interconnecting said intermediate drive shaft and each of said driven shafts, said last mentioned means including a part of said first mentioned means, a variable speed clutch interconnecting said normally idling shaft and said intermediate
- drive shaft, and means for operating said clutch for positively driving said normally idling shaft to accelerate said web to normal operating speed.
13. A variable speed clutch for use in a multiple impression printing press comprising a normally idling shaft, a driven shaft, a gear secured to said normally idling shaft, a gear secured to said driven shaft, a drum surrounding said gears and rotatably supported on said driven shaft, a pinion carried by said drum and engaging said gears, and means for frictionally engaging said drum to vary its resistance to rotation whereby said normally idling shaft may be selectively driven at variable speeds from said driven shaft.
14. The combination defined in claim 13 wherein said driven shaft is hollow and said idling shaft extends through and beyond said driven shaft and wherein said first-mentioned gear is secured to the protruding portion of said idling shaft.
15. The combination defined in claim 13 wherein one end of said driven shaft is supported by an anti-friction bearing carried in the hub of said first-mentioned gear.
16. The combination defined in claim 13 wherein said last-mentioned means includes a frictional band surrounding and engaging said drum.
17. Means for operating a variable speed clutch used to initiate operation of the normally idling impression cylinder of a multiple impression web printing press having positively driven printing cylinders for driving the web and impression cylinder comprising a brake band, crank arms connected to the ends of said brake band and pivotally supported on a stationary portion of said press, a toggle linkage interconnecting the opposite ends of said crank arms and means for operating said toggle linkage.
18. The combination defined in claim 17 wherein said means comprises a solenoid magnet secured to said stationary portion of said press, a core operatively associated with said magnet and a link connecting said core to one link of the toggle linkage.
19. A drive mechanism for a multiple impression printing press having a normally idling impression cylinder and positively driven printing cylinders comprising a main drive shaft, a drive pinion on said main drive shaft, a master drive gear engaging said drive pinion, a plurality of driving gears angularly spaced around said master gear and meshing therewith, means for driving said printing cylinders from said last-mentioned driving gears, a normally idling shaft carrying said impression cylinder and rotatably supporting said master gear and variable speed clutching means interconnecting said master gear and said normally idling shaft whereby said idling shaft may be accelerated to operating speed independently of said driven printing cylinders.
20. In a printing press, a rotatable shaft, a printing cylinder mounted on said shaft, clutch means arranged upon said shaft, a second clutch means adapted to be rotated with respect to said first clutch means, means for driving said second clutch means, means preventing relative movement of said clutch means axially of said shaft and selective means for operatively interconnecting said clutch means whereby said printing cylinder may be driven or may remain idle at will.
21. In a printing press, a rotatable shaft, a

printing cylinder mounted upon said shaft, a sleeve arranged to rotate with said shaft, a second sleeve arranged to freely rotate upon said first sleeve, means for continuously driving said second sleeve, and selective means for operatively interconnecting said sleeves whereby said printing cylinder may be driven or may remain idle at will.

22. In a printing press, a printing cylinder shaft, drive means for said shaft, clutch means carried by said shaft and manually operable to clutch said shaft to said drive means, said clutch means comprising a pair of separate concentric

sleeves and a selectively adjustable pin engaging in openings in said separate sleeves, one of said sleeves being connected to the drive means and the other to the shaft.

23. In the combination above defined in claim 5 22, a manually operable control wheel operatively connected to one of said sleeves.

24. The combination defined in claim 9 wherein the clutching elements comprise individual clutch members associated with the drive to 10 each printing cylinder.

EMIL ERICKSSON.
